EDGE FINISHING MACHINE

Thomas G. Winnett, Whitman, Mass., assignor
to United Shoe Machinery Corporation, Pater-
son, N. J., a corporation of New Jersey

Application December 31, 1936, Serial No. 118,615

6. Claims. (Cl. 69—1)

This invention relates to machines for finishing the edges of pieces of sheet material and is herein illustrated as embodied in a machine for finishing the edges of pieces of upper leather, such as may be used in boots and shoes. It has been herein illustrated as embodied in a machine of the type shown in Letters Patent of the United States No. 1,939,682, granted February 5, 1935, on the application of J. B. Coffey.

10 Machines for finishing the edges of pieces, such as leather, by shrinking the margin and curling the edge, commonly employ a U-shaped searing tool which is pressed against the margin of the flesh side of the leather and frequently 15 employ a plow positioned beside the crossbar of this U-shaped tool to assist in turning up or curling the edge of the material as it is shrunk by the action of the heated tool. When a tool of this character is heated electrically by the passage of current through the crossbar, the latter 20 preferably is of substantially uniform cross section in order that the heating effect may be uniform along the length of the crossbar. This tool is heated to approximately a red heat and although the material employed is chromel, an 25 alloy adapted to withstand such intense heat, the cross section of the tool is necessarily not very large. Consequently, the crossbar of the tool sometimes is bent upwardly by the work. At 30 other times, the crossbar is distorted outwardly away from the plow when, for some reason, the work is jammed between the tool and the plow, as by the carelessness of an operator in presenting the work.

35 An object of the invention is to guard against the distortion of the tool by means which provides an auxiliary support for the crossbar.

As illustrated and in accordance with features of the invention, the tool-supporting device comprises an arm the end of which is notched to rest against the upper and outer sides of the crossbar, thereby furnishing support against distortion in two directions and without radically affecting the temperature of the crossbar.

45 The arrangement will be best understood from a consideration of the following description, taken in connection with the accompanying drawing, in which

Fig. 1 is an end elevation of the tool-carrying means;

Fig. 2 is a side elevation showing the tool and the adjacent plow in section;

Fig. 3 is a horizontal section through the tool support, looking down on the crossbar and the auxiliary supporting device, and

Fig. 4 is an elevation showing in detail the arrangement of the auxiliary tool-supporting device.

The searing tool 10 of the illustrated machine is substantially U-shaped, having a crossbar 12 extending between two vertically positioned legs 14 and 16. The crossbar of this tool is pressed against the flesh side of a piece of leather 20 as the latter is carried past the tool either while held by the moving clamps 22, 24, as in the machine such as is described in the above-mentioned patent, or by any suitable means. Co-operating with the searing tool and positioned beside the crossbar 12 is a plow 26 which imparts an initial bend to the margin of the material and assists in the curling action of the machine.

The heating of the tool is effected by electric current supplied through heavy conductors 28 and 30, the downturned ends of which are grooved, as at 32, to receive the legs of the searing tool, which latter is held in place by sleeves 34 and 36. Set screws 38 are threaded in the lower end of each conductor and bear against the legs 14 and 16 of the tool to press them against the sleeves 34 and 36 which are also provided with grooves corresponding to the grooves 32 in the supports. A depending lug 40 on the sleeve 34 and a similar lug 42 on the sleeve 36 rest against the legs of the tool to strengthen them against lateral deflection. Pins near the upper ends of the grooves 32 form stops against which the upper ends of the legs are rested.

In accordance with my invention, distortion of the crossbar 12 of the tool is avoided by providing an L-shaped supporting member 50, the lower portion of which is provided with a notch 52 (Fig. 2) resting on the upper and outer sides of the crossbar adjacent to its mid portion. The upright leg of the L-shaped support 50 is clamped 40 against the sleeve 34 by means of a clamp member 54 held in position by a clamp screw 56. Preferably, the support 50 is insulated, as by a sheet of mica, from the sleeve 34. By reason of the high temperature, a scale forms in the notch 45 52 which is quite effective in insulating the lower end of the support from the tool.

As in the patented machine, the conductor support 28 is positioned by insulated clamps 60 in a cap member 62 which is tiltable about pivot screws 50 64 as the adjusting screw 66 is turned to bring the crossbar 12 nearer to or farther away from the plow 26. The other conductor 30 is insulated from and clamped in a depending arm 70 which may be swung about pivot screws 72 as the length 55

of the crossbar 12 of the tool increases when it is heated. The cap 62 is carried by the pivot screws 64 on an arm 74 which, in turn, is movably supported by pivot screws 76 on the frame 80 of the machine. The vertical position of this arm is determined by a regulating screw 82 threaded in the arm 74 and having a ball-shaped lower end 84 which is held in position on the frame by means of a slide moved in and out by a hand screw 86 10 to lock or release the arm.

In the use of the machine, the tool 10 is adjusted with respect to the plow 26 by first bringing it into contact with the plow by adjusting the screw 66. This will result in an obvious cooling of the 15 searing tool. The screw 66 is then turned to move the tool away from the plow just far enough so that it resumes its normal heat, as indicated by the color. The L-shaped support 50 is adjusted in its clamp so that the notched end thereof touches lightly against the crossbar of the searing tool without causing the color of the crossbar to change because of heat loss. An oxide or scale is apparently formed in the notch of this support which insulates the support from the 20 tool. Electrical insulation of the lower end of the support from the tool is not needed because of the insulation of the upper end of the tool from its support.

Having described my invention, what I claim 30 as new and desire to secure by Letters Patent of the United States is:

1. In a machine for treating the edges of leather, a U-shaped searing tool having legs connected by a crossbar, means for supporting said 35 legs, and auxiliary means for supporting the crossbar against upward bending.

2. In a machine for treating the edges of leather, a U-shaped searing tool having legs connected by a crossbar, means for supporting said legs, and auxiliary means for supporting the crossbar against lateral bending. 5

3. In a machine for treating the edges of leather, a U-shaped searing tool having legs connected by a crossbar, supports for said legs, and means carried by one of said supports engaging a mid portion of the crossbar to prevent its distortion. 10

4. In a machine for treating the edges of leather, a U-shaped searing tool having legs connected by a crossbar, supports for said legs, and means carried by one of said supports and 15 having a portion overlying the mid portion of the crossbar.

5. In a machine for finishing the edges of leather, a U-shaped searing tool having legs and a crossbar, supports for said legs adapted to supply electric current thereto, a plow beside the crossbar, and means for supporting the crossbar against distortion laterally away from the plow. 25

6. In a machine for finishing the edges of leather, a U-shaped searing tool having legs and a crossbar, supports for said legs adapted to supply electric current thereto, a plow beside the crossbar, and an arm carried by one of said supports having a notched end engaging the crossbar on the side away from the plow to support it against upward and lateral distortion. 30
